UNITED STATES PATENT OFFICE

WARREN M. SAMPLE, OF MUNCIE, INDIANA

DESIGN FOR AN UPRIGHT DISPLAY RACK

Application filed May 26, 1932. Serial No. 43,906. Term of patent 3½ years.

To all whom it may concern:

Be it known that I, WARREN M. SAMPLE, a citizen of the United States of America, residing at Muncie, in the county of Delaware and State of Indiana, have invented a new, original, and ornamental Design for Upright Display Racks, of which the following is a specification, reference being had to the accompanying drawing, forming part thereof.

Figure 1 is a top plan view of the upright display rack, showing my new design;

Figure 2 is a front elevational view of the same;

Figure 3 is a side elevational view of the upright display rack; and

Figure 4 is a perspective view of the upright display rack.

I claim:—

The ornamental design for an upright display rack, as shown.
